UNITED STATES PATENT OFFICE.

HENRY H. CUMMINGS, OF NEWTON, MASSACHUSETTS.

MECHANICAL TIME-FUSE.

1,182,839.

Specification of Letters Patent.

Patented May 9, 1916.

Application filed August 23, 1915. Serial No. 46,781

To all whom it may concern:

Be it known that I, HENRY H. CUMMINGS, a citizen of the United States, and a resident of Newton, in the county of Middlesex and State of Massachusetts, have invented an Improvement in Mechanical Time-Fuses, of which the following description, in connection with the accompanying drawings, is a specification, like characters on the drawings representing like parts.

This invention relates to mechanical time fuses particularly adapted for use in connection with explosives of various types, such, for example, as shrapnel or other explosive shells, and also capable of use in other relations.

In order that the principle of the invention may be readily understood, I have disclosed a single embodiment thereof in the accompanying drawing wherein I have represented the invention as applied to a shrapnel or other explosive shell.

In the drawing: Figure 1 is a vertical, central section of a shrapnel or other explosive shell having my invention applied thereto; Fig. 2 is a horizontal section of said fuse upon the line 2--2 of Fig. 1; Fig. 3 is a detail view of the table and supported parts looking down in Fig. 2; Fig. 4 is a view of the same parts looking toward the left in Fig. 2; Fig. 5 is a view of the same parts looking up in Fig. 2; Fig. 6 is a plan view of the graduated tape preferably employed by me in the practice of my invention; and Fig. 7 is a sectional detail of the tape roll and its support.

Shrapnel and other explosive shells have been heretofore provided with powder units which are intended to be so manipulated as to burn in predetermined lengths of time. In actual practice, however, weather conditions cause variation in the rate of burning and inasmuch as the shell in its flight frequently rises to a comparatively great elevation above the earth, the action of the somewhat rarefied air is to affect and vary the rate of burning of the powder units.

In the many attempts to time the explosion of the shell, various escapement means have been employed. So far as I am aware, the so-called dead-beat escapement has been found most efficient. The rapidity of the beat of such escapement determines the time of explosion of the shell. It should be noted that shells have in certain cases an initial velocity

of about 2600 feet per second, it follows that a beat once a second would have little practical control over the explosion of the shell. Escapement mechanisms have been devised for explosive shells wherein there occur as many as 300 to 500 beats per second, the purpose thereof being to control the explosion of the shell with great accuracy and at predetermined points, or in the immediate vicinity thereof. In practice, however, such high number of beats results in inaccuracy of control. In the course of my experiments, I have ascertained that the slower the speed at which I may maintain a constant or approximately constant escapement, the greater the degree of accuracy of control.

My invention, therefore, in one aspect thereof contemplates the employment of a mechanical time fuse employing an escapement mechanism whereby great accuracy of control may be effected. While this result may be secured in many different ways, I shall set forth one form of mechanism for accomplishing the same.

Other objects of the invention will be set forth fully hereinafter.

Referring more particularly to the drawings, the body of the shell is indicated at 1, it being in part broken away. Such body may be made of the usual material and is adapted to contain bullets or other missiles and a suitable explosive. The upper portion of the body is of generally truncated, conical form, and is herein shown as having a flat, annular end 2 internally threaded at 3 for the reception of a fuse base 4 externally threaded at 5 and having an upstanding flange 6 suitably formed to receive a cap 7 which may be of spun brass or any other suitable material. The said cap is adapted to be positioned after the fuse mechanism and co-acting parts have been set. Herein the said flange 6 is provided with an annular groove 8 into which the internal bead 9 of the cap 7 may be snapped.

Mounted within the upper end of the fuse base 4 is a ring or annulus 10, which is adapted to turn with the shell in the rotation of the latter upon its axis imparted thereto by the rifling of the gun from which the shell is discharged. The said ring or annulus 10 is provided with an annular groove 11 upon its upper surface adapted to receive ball bearings 12 which also enter an annular groove 13 in a superposed ring

or annulus 14, which does not partake of the rotation of the shell upon its axis or at most partakes thereof to a limited extent, and is intended to be restrained from rotation upon the initial discharge of the shell by its own inertia. I have herein represented said rings or annuli 10 and 14 as having upon their inner surfaces annular grooves 15, 16 adapted loosely to receive a retaining ring 17 having flanges 18, 19 bent to enter said grooves 15 and 16. Said retaining ring 17 does not cause rotation of the ring or annulus 14 with the annulus 10, but serves merely to retain said members in proper relation with each other during the flight of the shell. Mounted within the retaining ring 17 is a central receptacle 20 adapted to contain black powder or other suitable charging material and having applied thereto a percussion cap 21 or other suitable portion of the detonating means.

I contemplate the provision of any suitable means to cushion the time fuse mechanism during the initial projection of the shell. For this purpose I preferably provide the fuse base with an annular chamber 22, or if desired, with a plurality of pockets, and therein I position preferably some plastic material which will cushion the fuse mechanism without, however, imparting a rebound thereto. For this purpose I preferably place in said chamber or pockets a suitable quantity of sculptors' modeling clay indicated at 24, the same being preferably mixed with glycerin. I also preferably provide air spaces, such, for example, as indicated at 25, 26, whereby I obtain a cushion composed in part of plastic material and in part of imprisoned air. The action of such a cushion is to yield at the initial discharge of the shell, thereby cushioning the fuse mechanism, without causing a rebound thereof. Within the scope of my invention other suitable cushioning means may be employed.

Fast to the ring or annulus 14 is the support for the fuse timing mechanism. In this form of my invention I provide a disk-like base 27 fast with the ring or annulus 14 and having secured thereto or formed therewith arms or projections 28, 29 meeting or merging into each other at their upper ends, as indicated most clearly in Fig. 1. Said arms or projections are relatively narrow as indicated most clearly in Fig. 2, and constitute an inclosure and partial support for the fuse timing mechanism. Centrally of the base 27 I provide an upright tube 30, preferably rigid with said base and herein shown as riveted into the central opening 32 in said base 27. Within the said tube 30 I loosely position a firing pin 33 constituting a portion of the detonating means and so located that its lower, sharpened end 34 will at the suitable time strike the percussion cap 21 and ignite the power charge within the receptacle 20.

The said firing pin 33 is provided with a collar or shoulder 35 limiting the upward movement of said pin by contact with the under surface of the base 27.

In order to prevent premature movement of the firing pin and the consequent ignition of the charge, I may provide any suitable means. Herein for the purpose I have represented the upper end of the pin 33 as provided with a head 36 somewhat spaced from the upper end of the tube 30, in the position of the parts shown in Fig. 1. Between the upper end of said tube 30 and the head 36 of the pin 33 I position a yoke-like wedge 37 adapted upon the initial discharge of the shell to be automatically removed from its position between the head 36 and the upper end of the tube 30, so as to permit the firing pin 33 to be driven against the percussion cap when said pin is struck by the hammer or other suitable means upon its release by the fuse timing mechanism. For this purpose I have represented the said yoke-like wedge 37 as pivoted at 38 upon a small, upright weight 39 having a depending arm 40 pivoted at 41. With the described construction of parts, upon the discharge of the shell, the weight 39 receives a relative outward or swinging movement upon its pivot 41, thus withdrawing the yoke-like wedge 37 from beneath the head of the firing pin 33 and leaving the latter in condition to be driven against the percussion cap 21 at the proper time.

In the disclosed embodiment of the invention, I provide the tube 30 with a collar or annular shoulder 42 and beneath the same I position with a running fit upon said tube a circular table 43, the latter having an upstanding, central flange 44. Between the table 43 and the base 27 I position a suitable spring or springs 45 tending normally to hold said table 43 against the collar or shoulder 42, but permitting it to yield with respect thereto. In order to restrain the table and supported parts of the fuse mechanism from rotation with the shell in its flight or markedly to retard rotation of the table therewith, and particularly during the initial position of said flight, I provide said table with an upstanding weighted portion 46 which is eccentric to the axis of rotation of the shell. I have herein represented the upper end of said weight 46 as provided with a bearing 47 to receive a depending pin 48 positioned axially of the shell and supported by the arms 28, 29 at their meeting point. Said pin 48 is of sufficient length to support said weight when the table 43 moves, relatively, toward the base 27. The said weight 46 may be suitably recessed or otherwise shaped to permit portions of the fuse mechanism to be supported beneath the same upon the table 43.

In the flight of the shell the ring or annu-

lus 10 rotates therewith, but the ring or annulus 14, being free therefrom, need not partake of such rotation. The action of the weight 46 is to restrain from rotation or to retard the rotation of the table 43 and parts supported thereby and also the base 27 with its upstanding arms 28, 29, and particularly during the initial flight of the shell.

In the disclosed embodiment of my invention, I provide an escapement mechanism by means of which I control the time or period of operation or movement of the firing pin 33 and preferably I provide a plurality of escapement devices which are arranged to operate out of unison or non-synchronously. In the course of my experiments, I have ascertained that by providing a plurality of escapement devices and securing a resultant or composite movement of some suitable element or part, I may thereby obtain great accuracy of control. In the disclosed embodiment of my invention, I have provided an element to which I am enabled to impart, or which I permit to partake of, a substantially continuous movement in one direction. This I preferably do by providing a pair or other plurality of escapements operating alternately or out of unison and in such manner that each escapement device permits a movement of said element to be immediately or substantially immediately followed by a permissive movement of said element through or controlled by the other escapement. In this manner, I may obtain, through a dead-beat or other suitable escapement, the operation of said element at such a constant or otherwise suitable speed as to control the explosion of the shell with great accuracy and at the point desired or in the immediate proximity thereof.

In the disclosed embodiment of my invention I mount upon the table 43 a bracket 49 having upstanding members 50, 51 where-in I position a horizontal shaft 52, the bearing for said shaft 52 in the bracket member 50 being slightly elongated as represented at 53 in Fig. 5, so as to permit a slight rocking motion of said shaft from one end thereof as a pivot, to and from the plane of the sheet, viewing Fig. 4. The construction of parts is such that the said shaft may have a slight pivotal movement in the bracket member 51 in effecting such rocking motion. Fast upon one end of said shaft is a beveled gear 54 adapted to mesh with beveled pinions 55 and 56 loose upon the stud 57 rising from the table 43. The beveled pinion 55 has fast therein an escapement ratchet 58 shown most clearly in Fig. 2, and the beveled pinion 56 has fast therein an escapement ratchet 59, the teeth whereof are oppositely positioned with respect to those of the ratchet 58.

Surrounding the shaft 42 is a coiled

spring 60, one end 61 whereof is secured to a collar 63 fast upon said shaft 52. The other end of said spring is fixedly secured to a collar 64 loose about the shaft and having a sleeved portion 55 extending into a split portion 66 of the bracket 50, said split portion of said bracket being provided with a set screw 67 by means of which it may be tightened about the sleeve of said collar 64. The collar 64 is provided with one or more radial sockets 68, by means of which the collar may be turned in order to wind up the coil spring 60, thereby to give it sufficient tension to turn the shaft 52 when rotation thereof is permitted by the escapement ratchets 58, 59. Inasmuch as one end of said spring 60 is fast to the shaft 52 and the other end of the spring is secured to a support, the tendency of said spring 60 is to impart a movement of rotation to the shaft or element 52 in one direction, such movement being governed or controlled by the escapement ratchets 58, 59.

In the disclosed embodiment of my invention, I employ the shaft or element 52 to impart movement to a controller for the hammer or other means by which the firing pin 33 is operated. Herein for the purpose I provide a tape 69 shown in Fig. 6 and which may be of any suitable material, such, for example, as paper or ribbon. The said tape is provided with graduations 70 reading from the left toward the right in Fig. 6, and preferably with an ungraduated portion 71 which may be secured by inturning the ends 72 thereof into a slot in a drum 73 fast upon the shaft 52 and having a flange 75 shown most clearly in Figs. 3 and 4. Between the flange 75 of the drum and the member 51 of the bracket 49, I position a collar 76 upon the shaft 52 and I tighten the said drum with its flange against said collar to a sufficient extent by a thumb nut 77 upon the threaded end 78 of said shaft. Rotation of said shaft 62 thus tends to wind the tape 69 upon the drum 73 and to unwind it from the support. The said tape 69 may be coiled upon any suitable support. Herein for the purpose I have represented a bracket 79 secured to and upstanding from the table 43 and having laterally extending therefrom a short threaded pin or spindle 80 adapted to receive thereon a drum 81 having a flange 82. The said pin or spindle 80 may have an annular shoulder thereon against which may be positioned a thumb nut 83 received upon the threaded end 84 of said pin or spindle, thereby to hold said drum in position but to permit the tape to be unwound therefrom by the rotation of the shaft or element 62.

Between the drums 73 and 79 the tape extends in a substantially straight or flat condition and passes beneath two looped guides 85, 86 secured to the table 43 and suitably

spaced from each other. Between said guides 85, 86 and beneath the tape I position an arm 87 connected with the hammer mechanism, the construction and arrangement 5 of parts being such that when the tape has been sufficiently wound upon the drum 73 to be withdrawn from the guide 85, the arm 87 of the hammer mechanism is released, thus releasing the hammer and permitting 10 it to strike the firing pin 33 at the prearranged time and thereby to explode the shell.

In the vicinity of the tape 69 I position a suitable gage 88 by means of which the 15 tape may be initially set so that it will act to release the arm 87 at a prearranged or predetermined time or period. The graduations upon the tape may indicate periods of time and I may thus control the period 20 of explosion of the shell within a very minute fraction of a second. The arm 87 laterally extends from an arm 89 of a bell crank lever pivoted at 90 upon the table and having a second arm 91 provided with a 25 notched portion 92 which receives the end of an arm 93 of a hammer pivoted at 94 and provided with a head 95 which, when the hammer is released, strikes the head of the 30 firing pin 33 and drives the same against the percussion cap 11. The hammer lever is provided with a suitable spring 96 coiled about the pivot thereof and so supported that it tends to throw the hammer head with 35 force against the firing pin when released by the tape.

Upon the table 43, as shown most clearly in Fig. 5, I mount a bracket or casing 97, wherein is supported the spindle 57 whereon the escapement ratchets and their bevelled pinions are loosely mounted. Within 40 said casing or bracket I also mount in a preferably upright position the shaft 98 of any suitable escapement operating device. I have herein represented the said shaft as 45 having fast thereon a balance wheel 99 and a hair spring 100 which may be of any suitable construction, not herein necessary more fully to describe. I also mount in an upright position within the casing or bracket 50 97 a shaft 101 having fast thereon oppositely positioned, double-ended pawls or pallets 102, 103, which control the operation of the escapement ratchets 58, 59. Fast upon the shaft 101 is an arm 104 extending to 55 ward the balance wheel and having its end suitably mounted upon the pin 105 thereon, whereby in the usual operation of the balance wheel the said arm 104 is rocked to and fro, thereby to oscillate the shaft 101 with 60 its oppositely set pawls or pallets 102, 103.

In order to prevent operation of the balance wheel prior to the discharge of the shell, I may provide any suitable means. Herein and as shown most clearly in Fig. 65 2, I have provided a bracket 106 having a

pivotal portion 107 wherein is frictionally received a brake member 108 having a weighted outer end 109 and an inner angular end 110 adapted to enter a notch in the periphery of the balance wheel and to restrain 70 the same from movement. The initial flight of the shell effects a movement of the weighted end 109 of the brake in such direction as to remove the angular end 110 from the balance wheel, thus permitting the 75 same to begin its movement, thereby to permit alternate movements of the escapement ratchets 58, 59.

It will be clear from the foregoing description that the bevelled gear 54 is in mesh 80 with the bevelled pinions 55 and 56 of the escapement ratchets 58 and 59. Each bevelled pinion 55, 56 is temporarily restrained from movement by its escapement ratchet, but the construction and operation of the 85 parts are such that instantly upon the release of the ratchet 58 and its pinion 59 the shaft 52 receives movement of rotation from its coil spring 50, and upon said ratchet 58 and its pinion 55 being again held from action, the ratchet 59 and the pinion 56 immediately acts to give movement of rotation in the same direction to the shaft 52 so that I may in this manner render the movement 90 of the shaft 52 substantially constant or with but very slight and practically imperceptible periods of dwell in between. Thus the tape 69 may be drawn along at a substantially constant rate and thereby very accurately control the time of firing. 100

Owing to the fact that the shaft 52 receives a pivotal mounting in the bracket 51 and may vibrate slightly in its bearing in the bracket member 50, it will be evident 105 that the bevelled pinion 54 has a driving relation first with the bevelled pinion 55 and then with the bevelled pinion 56 between and relative to which it has a slight rocking or vibrating movement, so that when one of said pinions 55 or 56 is restrained 110 from rotative movement by its escapement ratchet 58 or 59, the rotation of the bevelled gear 54 is arrested thereby at its point of mesh and the diametrically opposite teeth of bevel gear 54 impart rotative movement 115 to the other pinion, so that the shaft 52 is given a movement of substantially constant rotation through the agency of the coil spring 60.

From the foregoing description, it will 120 be evident that I have provided a mechanical time fuse peculiarly adapted for explosive shells but capable of use in other relations. The construction of parts is such that the fuse mechanism is cushioned during the flight of the shell or during the initial portion of the flight and likewise is restrained from rotative movement with the shell or has such movement sufficiently retarded to protect and prevent derangement 125 130

of the fuse mechanism. Moreover, the structure of the fuse mechanism is such that it will operate with great accuracy irrespective of weather conditions and irrespective 5 of the height of the shell above the level of the sea.

Although I have described my invention with particular reference to an explosive shell, it is obvious that it is adapted for use in other relations. The escapement is not herein claimed broadly as the same is broadly claimed in another application.

Having thus described one illustrative embodiment of my invention, I desire it to be understood that, although specific terms are employed, they are used in a generic and descriptive sense and not for purposes of limitation, the scope of the invention being set forth in the following claims.

20 Claims:

1. An explosive projectile adapted to rotate in its flight, a mechanical time fuse carried by the projectile, but independent in operation of the said rotation of the projectile, and means to retard said fuse from rotation with the projectile.

2. An explosive projectile adapted to rotate in its flight, an escapement-controlled mechanical time fuse carried by the projectile but independent in operation of the said rotation of the projectile, and means to retard said fuse from rotation with the projectile.

3. An explosive projectile adapted to rotate in its flight, a mechanical time fuse carried by the projectile but independent in operation of the said rotation of the projectile, and a weight to resist centrifugal action and thereby to retard said fuse from rotation 40 with the projectile.

4. An explosive projectile adapted to rotate in its flight, a mechanical time fuse carried by the projectile but independent in operation of the said rotation of the projectile, a table within the projectile carrying said fuse, and means to retard said fuse from rotation with the projectile.

5. An explosive projectile adapted to rotate in its flight, a mechanical time fuse carried by the projectile but independent in operation of the said rotation of the projectile, a table within the projectile carrying said fuse, and a weight to resist centrifugal action and thereby to retard said fuse from rotation 55 with the projectile.

6. An explosive projectile adapted to rotate in its flight, a mechanical time fuse carried by the projectile but independent in operation of the said rotation of the projectile, cushioning means for said fuse and means to retard said fuse from rotation with the projectile.

7. An explosive projectile adapted to rotate in its flight, an escapement-controlled mechanical time fuse carried by the projec-

tile but independent in operation of the said rotation of the projectile, cushioning means for said fuse and means to retard said fuse from rotation with the projectile.

8. An explosive projectile adapted to rotate in its flight, a mechanical time fuse carried by the projectile but independent in operation of the said rotation of the projectile, plastic cushioning and rebound-preventing means for said fuse, and means to retard said fuse from rotation with the projectile.

9. A mechanical time fuse having a plurality of non-synchronized escapements, an element to which movement is transmitted by each of said escapements, means whereby said escapements conjointly impart a substantially continuous movement to said element, and a detonation controlling strip operated by said element.

10. A mechanical time fuse having a plurality of non-synchronized escapements, an element to which movement is transmitted by each of said escapements, means whereby said escapements conjointly impart a substantially continuous movement to said element and a detonation controlling strip wound by said element.

11. A mechanical time fuse having a plurality of non-synchronized escapements, an element to which movement is transmitted by each of said escapements, means whereby said escapements conjointly impart a resultant movement to said element and a detonation controlling strip operated by said element.

12. A mechanical time fuse having a plurality of non-synchronized escapements, an element to which movement is transmitted by each of said escapements, means whereby said escapements conjointly impart a resultant movement to said element and a detonation controlling strip wound by said element.

13. A mechanical time fuse having a plurality of non-synchronized escapements, a shaft to which movement of rotation is transmitted by each escapement, means whereby a resultant movement of substantially constant rotation is transmitted by said escapements to said shaft, a detonating device and a controlling strip therefor operated by said shaft.

14. A mechanical time fuse having a plurality of non-synchronized escapements, a shaft to which movement of rotation is transmitted by each escapement, means whereby a resultant movement of substantially constant rotation is transmitted by said escapements to said shaft, a detonating device, and graduated means operated by said shaft to control detonating device.

15. A mechanical time fuse having a plurality of non-synchronized escapements, a shaft to which movement of rotation is transmitted by each escapement, means whereby a resultant movement of substan-

- tially constant rotation is transmitted by said escapements to said shaft, a detonating device, and a graduated strip adapted to be wound by said shaft and controlling said detonating device.
16. A mechanical time fuse comprising a graduated strip, means to move said strip from one support to another, and a detonating device controlled by said movement of said strip.
17. A mechanical time fuse comprising an escapement, a graduated strip operatively connected to and adapted to be moved by said escapement, and a detonating device controlled in action by said strip.
18. A mechanical time fuse comprising an escapement, a graduated strip operatively connected to and adapted to be moved by said escapement, and including two supports from and under which the strip is wound, and a detonating device controlled in action by said strip.
19. A mechanical time fuse comprising an escapement, a graduated strip operatively connected to and adapted to be moved by said escapement, a support from which said strip is drawn by the action of said escapement, and a detonating device controlled in action by said strip.
20. A mechanical time fuse comprising a graduated strip, a support whereon said
- strip may be coiled, a second support spaced from the former and onto which the strip may be drawn, and a detonating device including a member held from movement by the portion of the strip between said supports.
21. A mechanical time fuse comprising a graduated strip, means to wind the same from one support onto another, and a detonating device controlled by said strip.
22. A mechanical time fuse comprising a graduated strip, a support whereon said strip may be coiled, means to wind said strip from said support onto another support, and a detonating device restrained from action by said strip.
23. An explosive projectile adapted to rotate in its flight, a mechanical time fuse carried by said projectile but independent in operation of the said rotation of the projectile cushioning means 22, 24 for the said time fuse and means including the weight 46, to retard said fuse from rotation with the projectile.
